UNITED STATES PATENT OFFICE

LEE JAY SMITH, OF VULCAN, ALBERTA, CANADA

COAL CUTTING MACHINE

Application filed May 3, 1930. Serial No. 449,577.

My invention relates to a portable machine for the cutting and mining of coal and is a quicker and cheaper method than the present system in use.

5 I more particularly describe my invention by means of the illustrations in the accompanying drawings in which:—

Figure 1 is a cross section through the casing showing worm, and worm wheels on auger 10 shaft extensions engaging with same.

Figure 2 is a sectional plan view through the casing showing the worm and worm wheels engaging with same.

Figure 3 is an upright view of the machine 15 and showing in dotted lines the machine in position for vertical drilling.

Figure 4 is a plan view of the machine showing the augers and cutting tools and anchor column.

20 Figure 5 is a cross section view of machine showing drills, augers and feed rods.

Figure 6 is a cross section view of machine showing augers and drills.

Figure 7 is a sectional view of the clamp 25 holding cutting tool.

Figure 8 is a cross section of the key.

Similar numerals refer to similar parts throughout the various views.

1 is the casing of the machine which is 30 formed in two parts and bolted together by bolts 2. A gasket 3 is fitted between the two halves of the casing 1 to form a tight joint.

Inside of casing 1 is a left hand worm 4 running the entire length of the machine and 35 having its ends journalled in tapered ball bearings 5. The ends of the worm 4 projecting beyond casing are formed to make connection to motor supplying the driving power.

A series of worm wheels 7 mesh with the worm 40 4 and form part of the shafts 8 which are coupled to augers 9 by means of the couplings 10, the shafts being held in the couplings by set screws 11. The shafts 8 are journalled in tapered ball bearings 12 set into casing 1.

45 Pipes 13 are screwed into casing 1 and form a covering for the augers 9 and are held rigidly in place by keys 14. Slots 15 are formed in the top and bottom of pipe covering 13 near the coupling 10 to allow of the removal

50 of the coal dust which accumulates around

the augers. Attached to ends of augers 9 are drills 16, made of triangular steel with a flared drill head 17. These drills are attached to ends of augers by means of a clamp 18. Cutting tools 19 of triangular steel are also attached to ends of augers by the clamp 18 and can be adjusted to any angle required and lengthened or shortened as desired.

55 The machine is held in position by means of a strap 20 diamond shaped, through the centre of which runs anchor pipe 21 having an internal thread 22 which engages with a vertical stem 23, the said stem working inside the anchor pipe 21 and forming part of a standard jack, being the continuation of the operating stem of same. Bolts 24 pass through strap 20 on either side of anchor pipe 21 to hold the strap in position. A collar 25 is bolted to anchor pipe 21 by bolt 26 and has a projection 27 to which the strap 20 is attached when removed from the horizontal position to its position for vertical drilling. The collar 25 can be raised or lowered on the anchor pipe 21 to suit the height 60 of the roof in the mine chamber.

65 Attached to either end of diamond shaped strap 20 are split housings 28 and 29, threaded to receive guiding rods 30 and 31, which are the extensions of two of the shafts 8 and 70 are attached to same by the couplings 32 and 33.

75 In operation, the machine is set up on the anchor pipe and held in place by diamond shaped strap and can be raised or lowered to any required height. The machine is 80 placed up close to the face of the coal so that the full length of the augers can be utilized. When the power is applied to the worm, the augers are engaged by same and turned by means of the worm wheels attached to the 85 shafts to which the augers are affixed, thus forcing the augers to penetrate the coal seam to the required depth. The depth that the augers penetrate is governed by the length of the guiding rods which are the extensions of 90 two of the augers and which are journalled in the split housings attached to the diamond shaped strap.

95 If it is desired to drill vertically into the roof of the chamber, the diamond shaped 100

strap is turned quarter way around, thereby turning the machine with it to a vertical position and the operation of drilling is carried on in the same manner as for horizontal drilling.

What I claim is:—

In coal cutting machines, a battery of boring members having driven shafts and operating connections, a casing containing said 10 operating connections and having shaft orifices, threaded guide rods extending from two of said driven shafts projecting through said orifices, a supporting bracket having rigidly held nuts mounted on said threaded guide 15 rods and flaring from either end to a central clamping portion and carrying clamping bolts and nuts, a spring clamping collar having a projection therefrom utilized in changing the position of said collar in said bracket 20 and an anchor column internally threaded and gripped in said collar and adapted to form an operating part of a standard lifting jack.

LEE JAY SMITH.
